US00D888230S

(12) **United States Design Patent** (10) Patent No.: **US D888,230 S**
Li et al. (45) Date of Patent: ** Jun. 23, 2020

(54) **DESKTOP ORAL IRRIGATOR**

(71) Applicants: **Jinfeng Li**, Hubei (CN); **Gang Wang**, Hunan (CN); **Qing Zhang**, Anhui (CN); **Xinquan Liu**, Sichuan (CN); **Xiaowen Liu**, Hunan (CN)

(72) Inventors: **Jinfeng Li**, Hubei (CN); **Gang Wang**, Hunan (CN); **Qing Zhang**, Anhui (CN); **Xinquan Liu**, Sichuan (CN); **Xiaowen Liu**, Hunan (CN)

(73) Assignee: **Flycat Electrical Co., Ltd.**, Xiantao, Hubei (CN)

(**) Term: **15 Years**

(21) Appl. No.: **29/645,274**

(22) Filed: **Apr. 25, 2018**

(51) LOC (12) Cl. **24-02**

(52) U.S. Cl.

USPC **D24/111**

EM 005246824-0004 * 5/2018

Primary Examiner — Lilyana Bekic

(74) Attorney, Agent, or Firm — Justin Lampel

(57) **CLAIM**

The ornamental design for a desktop oral irrigator, as shown and described.

DESCRIPTION

FIG. 1 is a bottom perspective view of a desktop oral irrigator showing our new design;

FIG. 2 is a bottom plan view thereof;

FIG. 3 is a top plan view thereof;

FIG. 4 is a right side view thereof;

FIG. 5 is a left side view thereof;

FIG. 6 is a rear view thereof; and,

FIG. 7 is a front view thereof.

The broken lines in the drawings depict portions of the desktop oral irrigator that form no part of the claimed design.

1 Claim, 7 Drawing Sheets
